CARRIER FOR KNITTING MACHINES

Martin Jauch, Irvington, N. J.

Application August 19, 1946, Serial No. 691,501

5 Claims. (Cl. 66—126)

1

This invention relates to carriers for knitting machines.

Such carriers consist essentially of a body portion attached at one end to an operative part of a knitting machine, with their other ends provided with thread guiding means secured thereto. Such guiding means, usually in the form of a thread guiding tube, have a short life due to the wearing away of the metal tube due to the frictional grinding action of the thread. It is therefore necessary to detach the carrier, and remove the thread guiding tube and replace it by another. As such tubes are secured by brazing or welding, such removal is difficult and time consuming. The replacement action is equally difficult and time consuming. Also, operators of such knitting machines, are, as a rule, indisposed to the making of mechanical repairs.

The object of this invention is to provide a carrier in which the thread guiding tube may be readily detached and another one may be replaced by anyone and with convenience and speed.

For this purpose, the invention consists of a carrier in which a thread guiding tube is detachably secured, which tube is self-contained with its means of attachment. More particularly, such a tube consists of a body portion of flexible tubing one end of which has secured thereto a thread guiding nozzle and the other end of which body portion has a tubular connection secured to a button member which has a cylindrical portion slightly larger in circumference than that of a receiving hole arranged in the carrier, to obtain a frictional hold of the button member with the body portion of the carrier. The tubular connection extends through the button member and preferably extends beyond the same in a flared thread inlet portion for the passage of the thread passing along the top of the carrier.

The invention will be more fully described hereinafter, embodiments thereof will be shown in the drawings, and the invention will be finally pointed out in the claims.

In the accompanying drawings,

Fig. 1 is a perspective view of the improved carrier;

Fig. 2 is a bottom view of the same;

Fig. 3 is a section taken on line 3—3 of Fig. 1;

Fig. 4 is a sideview of the front part of the carrier;

Fig. 5 is a top view;

Fig. 6 is a transverse section taken on line 6—6 of Fig. 5;

Fig. 7 is a plan view of the tubular portion of

2

the thread guiding member, with end views of the same;

Fig. 8 is a plan view of the connecting portion with end views of the same;

5 Fig. 9 is an enlarged longitudinal section taken one line 9—9 of Fig. 5 of the self-contained thread guiding means, showing only a part of the carrier, and

Fig. 10 is a perspective view of another known 10 form of carrier, but having the improvement made part thereof.

Similar characters of reference indicate corresponding parts throughout the various views.

Referring to the drawings, one form of known 15 carrier is shown in Fig. 1, and another form is shown in Fig. 10. Each has the improvement of like construction applied thereto.

The body portion 10 of the carrier 11, has openings 12 at one end to attach it to a knitting machine. The form of Fig. 1 has two ends, 13 and 14, flaring outwardly, and the form of Fig. 10 has two ends brought together in a pointed end 15. Each body portion 10 has an elongated slot 16. The thread 20 enters this slot 16, in the Fig. 1 20 form from above the body portion 10, and in the Fig. 10 form, after the thread 20 has first passed through an additional opening 17, necessary due to the shape of the attaching end of the carrier. The carriers 11 have grooves 18 for the guidance 30 of the thread. In both forms, the front parts 13 and 14 of the body portions are separated from each other to enable, a thread guiding member to be secured thereto.

The improvement consists in the thread guiding 35 member. The body portion of this member consists of a flexible tube 22 of known construction. A nozzle portion 23 has a sub-caliber portion 24 inserted into the bore of the flexible tube. The other end of the flexible tube 22 has a connecting 40 member secured in the bore of the flexible tube 22. The connecting member extends through a circular button member 25, and extends beyond the same in a flared portion 26, forming, preferably, an integral portion of the connecting 45 member 27.

The subcaliber portion 24 has an outer diameter of $4\frac{1}{2}1000$ of an inch, and the bore of the tube 22 has an inner diameter of $3\frac{3}{4}1000$ of an inch, in the embodiment shown. Thus, by forcing the subcaliber portion 24 into the bore of the tube 22, a tight fit and securing connection is obtained. Likewise, one end of the connecting member 27 has an outer diameter of $4\frac{1}{2}1000$ of an inch, and the forcing of it into the bore of the tube 22, brings about a secure hold.

The button member 25 has a cylindrical portion 28 with a diametrical bore 29, through which the connecting member 27 passes, these parts being held together by a frictional hold by different diameters as described.

The ends 13 and 14 of the carrier 11 have two opposed circular cutouts 32, one at each side of a slot 30, which separates the parts 13 and 14 of the carrier 11, the circular cutouts 32 being not quite semi-circular, but having a contour concentric with the cylindrical part 28 of the button member 25, the radii of the curvature being slightly less than that of the cylindrical part 28, with the centers of curvature being coincident to obtain a frictional hold, or, the bearing can be slightly eccentric or the cylindrical part 28 of the button member 25 can be eccentric, so that by a turning a hold is obtained. The cylindrical part 28 has an umbrella-like top 31 which extends circumferentially beyond the cylindrical part.

The nozzle 23, the flexible tube 22, the connecting member 27 and the button member 25 are all secured together, as described, as a self contained group or unit.

The unit is secured to the carrier by inserting the cylindrical part 28 into the circular opening formed by the almost semi-circular cutouts, and by reason of the diversity of the diameters, a frictional hold is obtained, the extending umbrella flange, abutting against the carrier, limiting the insertion movement of the button member. Thereby, the unit is secured to the carrier. The unit may be removed by an opposite movement and a new unit may be readily inserted. The directions of these movements are substantially perpendicular to the plane passing through the upper surface of the ends 13 and 14 (Figs. 5 and 10).

The unit has one end of the flexible tube seat itself between the walls forming the slot 30, there being a frictional hold here, in addition to the hold brought by the button member. The part of the tube with its nozzle extending beyond the walls of the slot 30 is flexible and permits the thread emanating from the nozzle to move freely in any angular direction, so as to cooperate with the needles of the knitting operation.

I have described several forms of my invention, but obviously various changes may be made in the details disclosed without departing from the spirit of the invention as set out in the following claims.

I claim:

1. In a carrier for knitting machines, the combination of a carrier having means for attachment to a knitting machine, and having a guiding point portion, with an opening, and a thread guiding attachment including a cylindrical button member adapted to seat in the walls of said opening, a flexible tube secured at one end to said button member by a connection member, and a thread guiding nozzle secured to the other end of said flexible tube,

2. In a carrier for knitting machines, the combination of a carrier having means for attachment to a knitting machine, and having a guiding point portion, with an opening, and a thread guiding attachment including a cylindrical button member adapted to seat in the walls of said opening, a flexible tube secured at one end to said button member by a connection member, and a thread guiding nozzle secured to the other end of said flexible tube, the outer diameter of the connection and the outer diameter of the nozzle being larger than the inner diameter of the flexible tube.

3. In a carrier for knitting machines, the combination of a carrier having means for attachment to a knitting machine, and having a guiding point portion, with an opening, and a thread guiding attachment including a cylindrical button member adapted to seat in the walls of said opening, a flexible tube secured at one end to said button member by a connection member, and a thread guiding nozzle secured to the other end of said flexible tube, the cylindrical member being of slightly larger diameter than that of the opening.

4. In a carrier for knitting machines, the combination of a carrier having means for attachment to a knitting machine, and having a guiding point portion, with an opening, and a thread guiding attachment including a cylindrical button member adapted to seat in the walls of said opening, a flexible tube secured at one end to said button member by a connection member, and a thread guiding nozzle secured to the other end of said flexible tube, the cylindrical member and the opening being eccentric to each other.

5. In a carrier for knitting machines, the combination of a carrier having means for attachment to a knitting machine, and having a guiding point portion including ends separated by a slot and an opening communicating with said slot, a flexible thread guiding nozzle having a part of its length in said slot and having a diameter substantially equal to the width of the slot, and means secured to said nozzle and detachably secured in said opening, to enable the nozzle to be removed by said last named means being removed from said opening and said part of the nozzle being removed from said slot and said means from said opening by a direction of movement substantially perpendicular to the plane passing through the upper surfaces of said ends, the removal of said means removing said nozzle.
